UNITED STATES PATENT OFFICE.

WILLIAM THOMAS CLARK, OF SCHENECTADY, NEW YORK, ASSIGNOR TO
TABOR MANUFACTURING COMPANY, OF PHILADELPHIA, PENNSYLVANIA, A CORPORATION OF NEW JERSEY.

ELECTRIC ENGINE.

SPECIFICATION forming part of Letters Patent No. 721,670, dated March 3, 1903.

Application filed October 1, 1902. Serial No. 125,489. (No model.)

To all whom it may concern:

Be it known that I, WILLIAM THOMAS CLARK, a citizen of the United States, and a resident of Schenectady, in the county of Schenectady and State of New York, have invented a certain new and useful Improvement in Electric Engines, of which the following is a specification.

This invention (Case B) relates to vibrator-engines primarily intended for use in connection with molding-machines of the type illustrated in Letters Patent of the United States numbered 533,401, 532,325, and 654,292, and dated, respectively, January 29, 1895, May 11, 1897, and July 24, 1900, one object of the invention being to utilize the electric current as the force for operating the hammer and another object being to secure a maximum effect of the force employed.

To these and other ends the invention consists of features of construction and combinations of devices hereinafter described, and more particularly pointed out in the appended claims.

The preferred form of the invention is illustrated in the accompanying drawings, forming part hereof, in which—

Figure 1 is a side elevation. Fig. 2 is a central longitudinal sectional view. Figs. 3 and 4 are detail views, and Fig. 5 is a diagrammatic view of the electrical connections.

In the drawings, reference *a* designates a tube preferably formed of a soft iron; *b*, metal disks fitting and secured in the ends of tube

a, and *c* an eye attached to one of the disks *b* and forming the means whereby the device may be attached to a pattern, pattern-carrier, vibrator-frame, or other part. Inside the shell or casing are two electromagnet-coils *d*, one at either end, and *e* marks short metal cores secured to the ends *b* and extending but part of the way into the said coils *d*.

Reference *f* marks insulating covers for the coils, and *g* metal plates embedded in said covers *f* and connected with the ends of said coils.

h marks bushings of insulating material inserted and fast in perforations in tube *a* opposite the plates *g*, and *i* *k* binding-screws en-

gaging with said bushings *h* and bearing against said plates *g* to make electrical connection therewith. The screws *i* are connected by a wire *l*, which is or may be a part of a current-supplying wire. The screws *k* are connected by wires *m* with contact-plates *n* *o*, one screw with one plate and the other screw with the other plate. The plates *n* *o* are secured to a block *p* of insulating material, which is secured to the tube *a* at one side of a slot *q* in said tube.

Within the hollow coils *d* is a metal rod *r*, which is shorter than the space between the opposed ends of cores *e*, and *s* is an iron disk fast to the rod *r*, said disk being between and free to move toward and from the opposed ends of coils *d*, while rod *r* is adapted to strike against the cores *e*. A spring *t* between disk *s* and one of the coils *d* moves the disk and rod to one extreme of their motion. The disk *s* has a rod *u* fast thereto, and said rod or arm *u* projects through the slot *q* and has a head *v* attached thereto outside of the tube *a*. The head *v* is bored transversely and longitudinally for the reception of insulating bushings *w*.

Reference *x* marks a contact-rod inserted in a bushing *w* and projecting between the plates *n* *o*, as shown, while *y* marks a binding-screw which engages with a bushing *w* and holds rod *x* in place, making electrical contact with the latter. The contact-rod *x* under the action of spring *t* is normally in contact with plate *o*.

At the side of slot *q* away from the block *p* is a similar block *z* of insulation, and the screw *y* is connected by a flexible wire *l* with a binding-screw *2* or contact which engages with block *z*. A spring-key *3* is also connected with block *z* and with a supply-wire *4* and is adapted to be closed down upon contact-screw *2* to close the circuit.

A comparison of Figs. 1 and 4 will show that the plate *o* is electrically connected with the right-hand screw *k* and plate *n* with the left-hand screw *k* in Fig. 1. It therefore follows that upon closing the key *3* the current passes through the coil *d* at the right in Figs. 1 and 2 and disk *s* and rod *r* are drawn to the right against the force of spring *t* until rod *r*

strikes the core-piece *e* at that end, by which time the rod *w* will have made contact with plate *n*, (having broken contact with plate *o* shortly after rod *r* began to move,) thus establishing the current through the left-hand coil *d*. This causes rod *r* and disk *s* to move to the left until rod *r* strikes the core-piece *e* at that end, by which time rod *w* strikes contact *o*, (having left contact *n* as rod *r* moved toward the left,) and so energizes right-hand coil *d*, and so on back and forth as long as key *3* is held down. The effect of the blows struck by rod *r* is communicated to the casing and to eye *c*, and so to the part to which eye *c* is attached. The blows of rod *r* are struck with great rapidity.

Obviously cores *e* may be omitted and rod *r* lengthened to strike ends *b* without departing from this invention.

20 What I claim as new, and desire to secure by Letters Patent of the United States, is—

1. In an electric engine, the combination of adjacent alined electromagnet-coils, a casing having short cores projecting into said coils, a reciprocatory striker between said cores, a disk on said striker and between the adjacent ends of said coils, adjacent contact-terminals connected with said coils, and an arm moved from one to another of said terminals by said disk to make and break the circuit through said coils alternately.

2. In an electric engine, the combination of adjacent alined coils, a casing, a reciprocatory striker within said coils, a disk on said striker and between the adjacent ends of the 35 coils, and circuit making and breaking means operated by said disk and energizing said coils in alternation.

3. In an electric engine, the combination of adjacent alined coils, a casing having short 40 cores projecting into said coils, a reciprocatory striker within said coils, a disk on said striker and between the adjacent ends of the coils, and circuit making and breaking means operated by said disk and energizing said 45 coils in alternation.

4. In an electric engine, the combination of adjacent alined coils, a casing having short 50 cores projecting into said coils, a reciprocatory striker within said coils, a disk on said 55 striker and between the adjacent ends of the coils, a spring for moving said disk and striker to one extreme of their motion, and circuit making and breaking means operated by said disk and energizing said coils in alternation.

Signed at Schenectady, in the county of Schenectady and State of New York, this 8th day of September, A. D. 1902.

WILLIAM THOMAS CLARK.
